UNITED STATES PATENT OFFICE

ROLAND H. MONEY, OF CINCINNATI, OHIO, ASSIGNOR TO THE CROSLEY RADIO CORPORATION, OF CINCINNATI, OHIO, A CORPORATION OF OHIO

DESIGN FOR A REFRIGERATOR CABINET

Application filed March 23, 1933. Serial No. 47,559. Term of patent 14 years.

To all whom it may concern:

Be it known that I, ROLAND H. MONEY, a citizen of the United States, residing in Cincinnati, in the county of Hamilton and State of Ohio, have invented a new, original, and ornamental Design for a Refrigerator Cabinet, of which the following is a specification, reference being had to the accompanying drawing, forming part thereof.

In the drawing:

Figure 1 is a perspective of the refrigerator cabinet taken from the front thereof showing my new design.

Figure 2 is a side elevation of the cabinet showing the bulge of the door.

The essential features of the design are a rectangular cabinet structure with a door which is bulged outwardly in a large panel-like form projected from an outlining margin which lies against the body of the rectangular cabinet, substantially as shown.

I claim:

The ornamental design for a refrigerator cabinet as shown and described.

ROLAND H. MONEY.
